UNITED STATES PATENT OFFICE.

AUGUSTE DENAYER, OF BRUSSELS, BELGIUM.

COMBINATION LOCK.

Application filed March 28, 1921. Serial No. 456,131.

To all whom it may concern:

Be it known that I, AUGUSTE DENAYER, a subject of the King of Belgium, residing at Brussels, in the Kingdom of Belgium, have invented certain new and useful Improvements in Combination Locks (for which I have filed applications and have obtained patents in Belgium, filed Aug. 9, 1918, Patent No. 273,646; Germany, filed Sept. 19, 1917, Patent No. 310,918; France, filed Dec. 17, 1919, Patent No. 510,997; Great Britain, filed Jan. 1, 1920, Patent No. 137,530; Holland, filed Nov. 25, 1918, Patent No. 5,297; Switzerland, filed Feb. 5, 1921, Patent No. 91,503), of which the following is a specification.

This invention relates to a secret combination lock for safes or the like, in which a number of wheels are set by the manipulation 20 of a single button or knob, which wheels together form the secret word or number of the combination.

The object of the invention is to enable the position of each sign (letter or number) 25 in a lock of that kind to be determined at will, independently of the other signs and without it being necessary, as has been the case with the locks of the same kind used hitherto, to have a constant relationship between the distance apart of the consecutive 30 signs, which always permits of the discovery of the secret of the combination by knowing the said relationship.

The lock according to the present invention 35 is mainly characterized by an arrangement of the operation of the wheels of the combination device by means of a single button which, on being rotated clockwise, drives a sign disc, and according to its own position relatively to the said disc, produced by rotation in the opposite direction, determines the number of the wheel driven, the sign of which is shown at this moment by the disc.

In other words, the combination is provided with a number of wheels, a sign disc and a single operating button which can occupy a number of different positions relatively to the sign disc, in accordance with 45 the number of the wheels used, the disc being coupled in each of the said positions to a given wheel of the combination, in order to allow of its movement at the desired moment.

In carrying out the invention in practice, the sign disc and the operating button are

arranged concentrically. The sign disc is rotated by the button in the clockwise direction by means of a pawl, and prevented from rotating in the opposite direction by 60 means of a ratchet device. The operating button is rotated in the clockwise direction in order to drive the sign disc, and executes a partial rotation in the opposite direction relatively to the sign disc, in order to produce consecutively the coupling of the various wheels, each of which must be brought into a certain position to enable the lock to be opened.

This coupling of the various wheels to the sign disc is obtained by providing the spindle of the operating button with a series of cams which, when they are brought into a suitable position by the partial rotation of the button in the anti-clockwise direction, 70 bring out of a sleeve forming the spindle for the sign disc, drivers which during the subsequent rotation of the disc in the clockwise direction, drive the wheels.

The combination device thus designed, 75 is preferably used with a lock arranged so that complete movement of the bolt is rendered possible only after destroying again the secret combination previously set in order to release the lock or bolt, in order to obviate the risk of the secret sign combination remaining when the door of the safe is closed.

A construction according to the invention, applied to the lock of a safe, is illustrated by way of example in the accompanying drawings:

Figure 1 is a front elevation of the lock,

Fig. 2 a horizontal cross-section through the door with the lock in plan.

Fig. 3 a back view of the lock, in which the mechanism of the secret combination is shown in section on the line C—D of Figure 7.

Figure 4 shows in a corresponding view 100 the position of the parts of the lock on partial movement of the bolt or in case of an attempt to open, with the combination destroyed.

Figure 5 is a partial view of the position 105 of the parts, with the bolt partly moved, when the combination has been previously set to the word or the number.

Figure 6 shows the position of the parts 110 at the moment of complete movement of the bolt after previous destruction of the combination.

Figure 7 is a horizontal cross-section through the combination device on the line A—B of Figure 1.

Figures 8—14 are detail views of the main parts of the combination device, that is, Figure 8 shows the sign disc with the operating button removed.

Figure 9 the ratchet wheels arranged behind the sign disc and intended to prevent the latter from turning in the anti-clockwise direction.

Figure 10 shows one of the wheels of the combination device.

Figure 11 one of the separation discs between the wheels,

Figure 12 shows separately the sleeve by means of which the sign disc can be coupled to the wheels of the combination device.

Figure 13 is a section through the said sleeve, and

Figure 14 shows in elevation and in three different sections, the sleeve which is used as a cam shaft for coupling the wheels of the combination device to the sign disc.

In the construction illustrated, it has been assumed that the lock has been fitted to the door 1 of a safe (Figures 1 and 2).

The bolt 2 of the lock is moved by means of a button 3 provided, on the inner side 30 of the door 1, with a disc 4 with two driver pins 5 and 6, Figures 3 and 4, which engage with a recess 7 of the bolt. This kind of control of the bolt is immaterial and if desired may be replaced by some other operating device, for instance a key.

The bolt 2 is guided by means of a slot 8 which has a stud 9 passing therethrough. On the said bolt is mounted an arm 10 pivoted at 11 and controlled by a spring 12 40 which tends to keep it in engagement with a stop pin 13.

If it is attempted to move the bolt 2 in order to open the door 1, the pointed end 14 of the arm 10 will engage with a recess 15 of a lever 16 which establishes mechanical connection of the lock proper with the combination device, and in the position indicated, renders impossible any movement of the bolt (Figure 4).

In the construction illustrated, the lever 16 swings about the point 17 on the base plate of a drum 19, Figures 3 and 7, secured to the plate 18 by means of screws 20. The plate 18 is in its turn screwed to the door 1. The drum 19 contains the combination device proper which, in the construction illustrated, comprises four wheels 21, 22, 23, 24, Figure 7, each of which is provided, as shown in Figure 10, with twenty-six notches 25, assuming that the secret combination is to be formed by letters. The wheels 21—24 are loosely mounted in the drum 19 in which they are carefully centered by the wall of the drum. They are separated from each other by discs 26, Fig-

ure 11, which are secured in an invariable position in the drum 19 by a projection 27 engaging with a groove 28, Figure 3, in the wall of the drum.

Each of the wheels 21—24 is moreover provided with a recess 29 which is deeper than the notches 25, and one edge of which extends in the radial direction, whilst the other edge 30 forms a cam surface. These recesses 29 are intended, as will be explained further on, to receive a transverse bar 31 provided at the end of a lever 16 projecting into the drum 19 through a lateral opening 32. The lever 16 is controlled by a spring 33. In order to keep the wheels 21—24 in the position given to them by the driving or operating device described below, pawls 34 rotatably mounted at 35 on the outer circumference of the drum 19 and controlled by springs 36, project through an opening 37 in the wall of the drum and engage with the notches 25. In order not to interfere with the action of the said pawls, each disc 26 is provided with a corresponding recess 38, Figure 11. The discs 26 are moreover each provided with a recess 39, which as shown dotted in Figure 3, corresponds to the opening 32 in the drum, through which passes the cross-bar 31 of the lever 16. In these conditions, the discs 26, when the recesses 29 of the four wheels 21—24 coincide, that is to say are set in the same radial vertical plane passing through the bar 31 of the lever 16, do not offer any obstacle to the engagement of the cross-bar 31 with the recesses 29. In this way, as is mentioned later on, the locking of the bolt is destroyed.

It will be seen that if each of the wheels 21, 22, 23, 24 is coupled to the letter disc in order to be brought to the above position, the four wheels give, when the four corresponding letters on the sign disc are read consecutively, a certain word which forms the secret of the combination. This driving or operation is effected in the following manner:

A spindle 40, Figures 3 and 7, passing through the centre of the drum 19, carries a sleeve 41 which is adapted to turn with the said spindle in a second sleeve 42. The latter is centered by means of a journal portion 43 turning in the bottom of the drum 19, and by means of a bearing surface in the plate 18. The sleeve 41 is coupled to the spindle 40 by means of a pin 41¹, Figure 14, engaging with a groove 41² of the spindle 40, so that the sleeve 41 participates in the rotation of the spindle 40. The spindle 40 and the sleeve 42 surrounding the same, pass through the wall 1 and terminate at their front ends in square wrench portions 45 and 46 respectively, Figure 9.

On the square 46 is mounted a letter disc 47 resting against the wall 1, and the square 45 carries an operating button 48. Between

the letter disc and the button 48, on the spindle 40 is mounted a wheel 49 with a number of notches 50, Figure 8, which corresponds to the number of the wheels 21-24 in the drum 19. With one of the said notches engages a pawl 51 mounted on the letter disc and controlled by a spring 52.

The sleeve 42 carries behind the letter disc 47, that is to say between the said disc and the wall 1, a toothed wheel 53, Figure 9, meshing with a small toothed wheel 54 which is mounted loosely between the letter disc 47 and the wall, and also between the toothed wheel 53 and a toothed rack 55 screwed to the wall 1.

Owing to this arrangement, the spindle 40, on the button 48 being turned in the clockwise direction, (arrow 56, Figure 8), turns the letter disc 47 by means of the wheel 49 and the pawl 51 engaging with one of the notches 50. If on the contrary the button 48 is turned in the opposite direction (arrow 57, Figure 8), the toothed wheel 53 driving the toothed wheel 54, jams the latter between itself and the toothed rack 55, so that the sleeve 42 and the disc 47 are prevented from participating in the rotation. The spindle 40 thus rotates alone with the notched wheel 49 which becomes disengaged from the pawl 51. This rotation continues until the moment when the pawl 51, under the action of the spring 52, springs into the next notch 50 of the wheel 49.

The operating button 48 can therefore drive the letter disc 47 only when turned in the clockwise direction; in the opposite direction it rotates alone to fractional extents determined by the notches 50 of the wheel 49, and accordingly, in the construction adopted, assumes consecutively four different positions relatively to the letter disc 47 which are indicated on the button by the figures 1, 2, 3, 4 marked on it, Figure 1, and which are brought consecutively under an index 80 of the letter disc.

The sleeve 42 is provided, in the plane of each of the wheels 21-24, with an opening 58, Figures 12 and 13, in which is mounted on a pin 59 a locking pawl 60 with a hook 61. The sleeve 41 placed over the spindle 40, acts as a cam shaft which determines the position of the locking pawls 60. To that end, the sleeve 41 is provided at its circumference with grooves 62, 63, 64, Figure 14, of different length, with which engage the locking pawls 60. In the construction illustrated, in which the combination device comprises four wheels 21, 22, 23, 24, the sleeve 41 has four cams. The first cam is constituted by the full or solid circumferential surface of the sleeve, whilst the other three cams are formed, as shown by the cross-section in Figure 14, by the bottom surfaces of the grooves 62, 63, 64.

If, in a given position of the sleeve 41,

relatively to the sleeve 42 (that is to say, of the operating knob 48 relatively to the letter plate 47) the sleeve 41 faces with its solid or full face the openings 58 of the sleeve 42, the four locking pawls 60 in the openings 58, are turned outwards, so that they are brought into the position shown in dotted line in Figure 13 or in full line in Fig. 3, in which the hook 61 projects from the sleeve 42.

If however the knob 48 is moved through a quarter revolution in the anti-clockwise direction relatively to the letter disc 47, one of the grooves of the sleeve 41, for instance the groove 64, is brought opposite the corresponding opening of the sleeve 42 so that during the subsequent joint movement of the two sleeves 41 and 42 in the clockwise direction, the corresponding pawl 60 remains in its opening. Owing to the different circumferential lengths of the grooves 62, 63, 64, each of the pawls 60 may be rendered inoperative by a partial rotation of the sleeve 41 relatively to the sleeve 42, with the exception of that pawl which rests permanently against the circumference of the sleeve 41 and for which no groove is provided.

The hooks 61 of the pawls 60 bring about the driving of the wheels 21-24 by acting on a driver 65 of a rim 66, Figures 3 and 10, provided inside each of the wheels. This rim is situated at times in the same plane as the wheel, has the same thickness and is connected so as to participate in its rotation in an arbitrarily variable manner, for the purpose of selecting the sign that is to form a part of the secret combination.

In the construction illustrated, each of the wheels 21, 22, 23, 24 has a central bore 67 within which is mounted the corresponding rim 66. The latter is provided at its circumference with twenty-six notches 68 with which engage two pawls 69, 70, Figure 10, mounted in recesses 71 of the wheel and controlled by the action of a double-acting spring ring 72 mounted in a circumferential groove of the wheel. By means of the two pawls 69, 70, the rim 66 is perfectly coupled to the corresponding wheel so as to rotate with it. The position of each rim relatively to the wheel, may be easily modified, however, by making the pawl 70 inoperative by the introduction of a pin 73 into a milled recess 74 having the shape, for instance, of three quarters of a circle.

Owing to the position of the recess 74 relatively to the recess 29 in each wheel 21, 22, 23, 24, all the recesses 74 are in alignment with each other and an opening 75 of the drum 19 when the recesses 29 are in one and the same radial plane. The pin 73 (Figure 7) may then be introduced through the opening 75 and pass through all the wheels as well as through the holes 76, Figure 11, in the intermediate discs 26, so that

it will lift out the pawls 70 of the four wheels 21, 22, 23, 24 and at the same time prevent the said wheels from rotating.

The lock described in the foregoing, as will be seen more particularly in Figures 3 and 7, is so arranged that the spindle 40 is held in the drum 19 by means of a nut 77 screwed on its screw-threaded end. The button 48 is secured to the square 45 of the spindle 40 by means of a countersunk screw rendered invisible in a suitable manner. The wall 1 has an index 79 intended to fix the position of the letter disc 47 and the latter has in its turn an index 80 by means of which the various positions of the button 48 relatively to the letter disc may be conveniently set. The lock proper is completed by a stop 81 secured to the bolt 2 and limiting the downward movement of the lever 16, and by a slide 82 provided with a projection 83, controlled by a spring 84 and normally engaging with the stop 85 of the bolt.

These auxiliary parts contribute to ensure perfect action of the lock and to render impossible any unauthorized opening of the same.

The working of the arrangement is as follows:

When the lock is closed, the parts occupy the position shown in Figure 3. The projection 83 of the slide 82 rests on the lever 16 at 86 and holds it lowered to such an extent that the cross-bar 31 is out of engagement with the notches 25 of the wheels 21, 22, 23, 24 which can therefore be turned by the operating button 48. If an attempt is made to move the bolt by means of the button 3 or by means of a key taking its place, its arm 10 strikes the lever 16 as already explained and as shown in Figure 4. The opening is therefore impossible. In order to make it possible, the cross bar 31 of the lever 16 must drop into the recesses 29 of the wheels 21, 22, 23, 24, so as to enable the lever 16 to assume a more horizontal position, as shown in Figure 5, in which the arm 10 passes under the said lever. In order however to set the recesses 29 in the radial plane passing through the cross-bar 31, the wheels 21, 22, 23, 24 must be brought into the position corresponding to the various letters of the secret word. To that end, by turning the button 48 in the direction of the arrow 57, Figure 1, its number 1 is brought under the index 80 arranged below the letter A of the letter disc 47. The sleeve 41, Figure 14, then assumes such a position relatively to the sleeve 42 that the four pawls 60 are forced out of their openings 58 by the solid circumference of the sleeve 41. The button 48 is thereupon turned in the direction of the arrow 56, Figures 1 and 8. The button then drives the letter disc 47 by means of the notched wheel 49 and the pawl 51, and the pawls 60 drive the four wheels 21, 22, 23, 24

by means of their hooks 61 acting on the drivers 65. This rotation is continued until the first letter of the secret word appears under the index 79. Thereupon the button 48 is again turned in the direction of the arrow 57 in order to bring the number 2 of the button under the index 80 of the letter disc 47. During this movement the letter disc remains stationary, for, as already explained, it is held fast owing to the jamming of the toothed wheel 54 between the wheel 53 and the toothed rack 55. Owing to the rotation of the spindle 40, the sleeve 41 is moved relatively to the sleeve 42 and brings one of the grooves, say 64, under the corresponding pawl 60, so that the latter is forced back into its opening and can no longer drive the corresponding wheel which thus remains stationary in the position given to it. The first wheel is thus set to the first letter of the word. Thereupon the button 48 is again turned in the direction of the arrow 56, the letter disc 47 being driven until the moment when the second letter of the secret word is under the index 79, whereupon the button 48 is again turned in the direction of the arrow 57 until the number 3 of the button is below the index 80. During that time the disc 47 remains stationary, whilst owing to the rotation of the sleeve 41 relatively to the sleeve 42, another pawl 60 is forced back into the corresponding groove, for instance 63, of the sleeve 41, owing to which the second wheel of the combination device is set to the second letter of the secret word.

As regards the third and the fourth letters of the word, the proceeding is exactly the same.

When in this way the four letters have been consecutively brought under the index 79, the bolt 2 is pushed back by means of the button 3 or of a key. The projection 83 releases then the end 86 of the lever 16, and the latter, under the action of the spring 33, drops with its cross-bar 31 into the recesses 29 of the wheels 21, 22, 23, 24, which are now all situated in the same radial plane. By continuing to push the bolt 2 by means of the button 3, the parts are brought into the position Figure 5, that is to say the arm 10 passes under the lever 16. The projection 83 of the slide 82 then strikes the finger 88 of the lever 16, so that during further retractive movement of the bolt, the slide 82 lags behind it, the spring 84 being compressed. The movement of the bolt is however limited by the distance it can move freely relatively to the slide 82, and in order to enable the bolt to be pushed farther into completely open position, the lever 16 must be lowered again in order to release the projection 83 from the finger 88. This is effected by destroying the secret word. To that end, the button 48 is again turned in the

direction of the arrow 57 so that the number 1 of the button is brought under the letter A and the index 80 of the letter disc 47, whereupon the button 48 and the letter disc 47 are given a complete revolution in the direction of the arrow 56 (clockwise). During this rotation the four wheels 21, 22, 23, 24 are also rotated and the cam faces 30 of the recesses 29 are forced against the cross bar 31 lifting the latter. The lever 16, owing to this movement assisted by the thrust of the slide 82 due to the action of the spring 84 depresses the lever 10 in opposition to the action of its spring 12, and the parts are brought into the position shown in Figure 6 in which, as will be seen, the slide 82 has passed in front of the finger 88 of the lever 16 and engaged again with the stop 85 under the action of the spring 84. The bolt 2 can then be moved by means of the button 3 or key in order to open the lock completely. If the bolt is then advanced again, all the parts are again brought into the position shown in Figure 3, in which any opening without the knowledge of the secret word, is rendered impossible.

If it is desired to alter the secret word, it is merely necessary, with the door open and after setting to the secret word used at the time, to introduce the pin 73 into the opening 75 of the drum 19. The pin then locks in the manner already explained, the wheels 21, 22, 23, 24 and lifts out the pawls 70, so that by means of the button 48, in the same way as for setting the word, each of the rims 66 can be turned consecutively into the position corresponding to the desired letter, it being merely necessary to set the corresponding letter under the index 79. If the pin 73 is then withdrawn again, the wheels 21, 22, 23, 24 will be again coupled to their rims, and the lock is ready to answer to the new secret word.

It will be seen that the numbers 1, 2, 3, 4 on the button 48, the object of which is to facilitate the setting of the said button in the consecutive positions relatively to the letter disc, indicate in reality the sequence of the wheels 21, 22, 23, 24 which are brought consecutively into the releasing position of the combination. It would also be possible, without difficulty, to use a still greater (and of course a smaller) number of wheels, provided that the button 48 is given a corresponding number of positions relatively to the letter disc 47 and that the sleeve 41 is fitted with a corresponding number of cams, so that in each new position of the button 48, one of the wheels 21, 22, 23, 24 is no longer driven by its pawl 60.

The invention is of course not limited to the constructional details adopted in the example illustrated. There is a considerable latitude in the selection of detail for carrying out the objects of the invention. It is

also obvious that the lock itself may be replaced by any other suitable construction co-operating with the combination device forming the main characteristic feature of the invention. The lock described however presents advantages in as far as it is closely connected to the parts of the combination device and does not allow of any movement of the bolt unless previously set correctly; again, it does not allow of any turning of the letter disc of the combination device until the bolt has been completely advanced, as in this case the projection 83 of the slide 82 releases the projection 86 of the lever 16, so that the latter, under the action of the spring 33, engages with the opening 32 of the drum 19 and engages with its crossbar 31 with the right angle notches 25 of the wheels 21, 22, 23, 24 so that the latter, and therefore the letter disc, are prevented from turning.

In order therefore to enable the letter disc 47 to be turned in the clockwise direction, and the secret word to be set, the bolt must be completely advanced; during that time the wheels 21-24 may be moved without the least noise or knock which in other kinds of secret locks, make it possible to guess the position corresponding to the letters set.

What I claim is:

1. In a combination lock, the combination of a spindle, a plurality of wheels and means between the spindle and said wheels for successively bringing the same into a definite angular relationship with each other, said means including mechanism operative to separately intercouple the spindle and the wheels to rotate the latter when the spindle is moved in one direction and operative to successively uncouple the said wheels by movement of the spindle in opposite direction.

2. In a combination lock, the combination of a spindle, a plurality of wheels and means between the spindle and said wheels for successively bringing the same into a definite angular relationship with each other, said means including mechanism operative to separately intercouple the spindle and the wheels to rotate the latter when the spindle is rotated in one direction and operative to successively uncouple the wheels when the spindle is moved to different angular extents in opposite direction.

3. In a combination lock, the combination of a spindle, a plurality of wheels mounted concentrically to the spindle, a cam sleeve surrounding the spindle and rotatable therewith, a second sleeve surrounding the cam sleeve, means operative to couple the second sleeve with the spindle when the latter is rotated in one direction and to hold it stationary when the spindle is rotated in opposite direction, pawls on the second sleeve movable in radial direction, the cam sleeve being constructed and arranged to suc-

- 6 sively move the said pawls outwardly when the spindle is moved to different extents relatively to the second sleeve and means between the separable wheels and the separate 5 pawls for effecting a coupling therebetween for rotation in one direction when the spindle and the two sleeves are rotated together.
4. In a combination lock, the combination 10 of a spindle, a plurality of wheels mounted concentrically to the spindle, a letter disk, means between the spindle, the letter disk and the wheels for operatively intercoupling the separate wheels and the letter disk to rotate interdependently when the spindle is rotated in one direction and for maintaining the same stationary when the spindle is rotated in the opposite direction.
5. Device according to claim 4 including 15 mechanism constructed and arranged to make the coupling means between the separate wheels on the one side and the spindle and the letter disk, on the other side, ineffective.
6. Device according to claim 5 in which the said mechanism includes coupling members movable with the spindle in one direction and means connected with the spindle for successively varying the position of the 20 said coupling members when the spindle is rotated in the opposite direction.
7. In a combination lock, the combination 25 of a spindle, a plurality of wheels concentric with the spindle, a letter disk concentric with the spindle, separate coupling members between the spindle and the wheels, means on the spindle constructed and arranged to successively make the different coupling members inoperative when the 30 spindle is rotated to different angular extents in one direction, means constructed and arranged to angularly move the coupling members with the spindle only when the latter is rotated in opposite direction and means for rotating the letter disk in one 35 direction concurrently with the angular movement of the coupling members.
8. In a combination lock, the combination 40 of a spindle, a plurality of wheels concentric with the spindle, a letter disk concentric with the spindle, a sleeve surrounding the spindle and carrying a plurality of coupling members adapted to operatively engage the separate wheels for movement 45 thereof in one direction, means between the spindle, the letter disk and the sleeve for interdependently rotating the letter disk and the sleeve when the spindle is rotated in one direction and for maintaining the 50 same stationary when the spindle is rotated in opposite direction, and means on the spindle operative, when the spindle is rotated to different angular extents relatively to 55 said sleeve to successively make said coupling members ineffective.

9. In a combination lock, the combination of a spindle, a letter disk concentric with the spindle, means on the spindle and the letter disk effective as a coupling when the spindle is rotated in one direction and ineffective as a coupling when the spindle is rotated in the opposite direction, and means for maintaining the letter disk stationary when the spindle is rotated in said opposite direction.

10. In a combination lock, the combination 70 of a spindle, a plurality of wheels concentric with the spindle, couplings between spindle and the separate wheels constructed and arranged to be effective only when the spindle is rotated in one direction, means for making the said couplings successively ineffective and means for varying the angular relation between the spindle and the separate wheels independently of the couplings.

11. In a combination lock, the combination 75 of a spindle, a plurality of wheels concentric therewith, couplings between the spindle and the separate wheels operative to normally impart rotary motion to the wheels when the spindle is rotated in one direction and to be inoperative when the spindle is rotated in the opposite direction, separate means for making the separate 80 couplings ineffective independently of said first means, a letter disk and means for interconnecting the spindle and the letter disk to cause the latter to move with the spindle when the latter is moved in the direction 85 in which motion is normally imparted to the wheels and to maintain the letter disk stationary when the spindle is rotated in opposite direction.

12. In a combination lock, the combination 90 of a spindle, a plurality of wheels, a letter disk, a plurality of coupling members normally co-operating with the respective wheels to angularly move them in one direction, a sleeve surrounding the spindle 95 and supporting the said coupling members, means interconnecting the spindle, the letter disk and the said sleeve to cause the letter disk and the sleeve to rotate when the spindle is rotated in one direction and to remain stationary when the spindle is rotated in the opposite direction, means connected 100 with the spindle for making said coupling members successively ineffective when the spindle is rotated to different extents in 105 such opposite direction and means for varying the angular relation between each wheel 110 and its coupling member.

In testimony whereof I have affixed my signature in presence of two witnesses.

AUGUSTE DENAYER.
